(57) **CLAIM**

The ornamental design for a picture frame and pen holder, as shown and described.

DESCRIPTION

FIG. 1 is a front perspective view of the picture frame and pen holder according to the design of the present invention; FIG. 2 is a front elevational view of the picture frame and pen holder shown in FIG. 1, with the rear view being the mirror image thereof;

FIG. 3 is a top plan view of the picture frame and pen holder shown in FIG. 1;

FIG. 4 is a bottom plan view of the picture frame and pen holder shown in FIG. 1, the structure depicted by means of broken lines being shown for illustrative purposes only and forming no part of the claimed design; and,

FIG. 5 is a front perspective view of the picture frame and pen holder shown in FIG. 1 with the movable support member shown therein.
